DESIGN FOR A FOUNTAIN PEN AND PENCIL CLIP

Karl Weisser, Union City, N. J., assignor to David Kahn, Inc., North Bergen Township, Hudson County, N. J., a corporation of New Jersey

Application May 19, 1938, Serial No. 77,285

Term of patent 14 years

To all whom it may concern:

Be it known that I, Karl Weisser, a citizen of Germany, residing at Union City, in the county of Hudson and State of New Jersey, have invented a new, original, and ornamental Design for a Fountain Pen and Pencil Clip, of which the following is a specification, reference being had to the accompanying drawing, forming a part thereof, wherein:

I claim:

The ornamental design for a fountain pen and pencil clip, substantially as shown and described.

KARL WEISSER.
